UNITED STATES PATENT OFFICE.

HENRY CAVE, OF HARTFORD, CONNECTICUT, ASSIGNOR TO THE FULLER BRUSH COMPANY, OF HARTFORD, CONNECTICUT, A CORPORATION OF CONNECTICUT.

BRUSH.

Application filed June 20, 1925. Serial No. 38,581.

My invention relates more especially to that class of brushes that are adapted for use in removing dust and dirt, as ashes, from floors, hearths and other similar surfaces, and an object of my invention, among others, is the production of a brush of this type that shall be extremely simple in construction and that may, therefore, be produced at a minimum cost, one that is particularly efficient for the purpose for which it is designed, and one the construction of which shall be such as to produce a brush having a very neat appearance.

One form of a brush embodying my invention and in the construction and use of which the objects herein set out, as well as others, may be attained, is illustrated in the accompanying drawings, in which—

Figure 1 is a side view of brush embodying my invention.

Figure 2 is an isometric view of my improved brush with the handle removed.

Figure 3 is a similar view showing the construction and application of the cover sleeve, 25 the brush being broken off.

Figure 4 is a detail view of that end of the handle to which the brush is secured.

In the accompanying drawings the numeral 5 indicates the handle of my improved brush which handle may be composed of any suitable material, as wood, with a hole extending inwardly at the end thereof and with a ferrule 6 applied to such end in any suitable manner. This end of the handle 35 and the end of the ferrule are provided with a crosswise groove 7 preferably formed on the arc of a circle.

The brush usually comprises a core 8 of twisted wire to which bristles 9 are secured in the twisting operation, in a manner that will be readily understood, this core being bent into a frame-like structure of oblong shape, the ends of which frame are rounded. The ends 10 of the core are bent at substantially right angles to the main part of the frame and are forced into the hole in the end of the handle, said hole being enough smaller 45 than the ends 10 to retain the latter securely in place.

The ends of the brush 11, that is composed 50 of the bristles above described, are cut off, preferably square with the core, as shown in Figures 1 and 2, thereby leaving a space 12 between the opposite ends of the brush, these squared ends being located at some distance

from the handle 5, and the wire core between these squared ends being bare and devoid of bristles.

A retaining sleeve 13, in the form of a tube, is made from sheet metal of a length 60 substantially that of the width of the space 12, this sleeve being preferably of rounded form on its upper side and the edges 14 are brought together at the under side thereof, that is, on that side toward the bottom portion 65 15 of the brush, in a convenient form of construction these edges being located at an angle to each other, and as shown in Figure 3 of the drawings, altho this form is not absolutely essential. A hole 16 is 70 formed through the top side of the sleeve at about its lengthwise center and the ends 10 of the wire core are extended through this hole and into the hole hereinbefore described, as being formed in the end of the 75 handle, and when such ends 10 are secured in the hole in the handle the rounded part of the sleeve will rest snugly in the recess 7, and when such ends are inserted through the hole 16 said ends are securely held to 80 maintain the shape of the frame.

In the preferred form of construction the ends 10 of the wire core are inserted through the holes 16 before the sleeve is finally bent into tubular form, this latter operation 85 taking place just before the ends 10 are inserted in the hole in the end of the handle.

It will be seen that a brush thus constructed is very simple in construction, light, durable, and extremely neat in appearance, 90 and the cover sleeve effectually obscures the otherwise bare portion of the twisted wire core and also serves as a shield to prevent marring of articles of furniture or other structures, the sleeve being smooth as compared with the twisted wire core.

A brush frame of this character is naturally more or less flexible, and this flexibility would tend in use to loosen the ends contained in the handle 5, and the sleeve 13, 100 is therefore, provided for the purpose of strengthening the brush ends and imparting rigidity to them, whereby this springing action is reduced to a minimum and loosening of the ends of the brush in the handle by 105 such action is greatly lessened.

In accordance with the provisions of the patent statutes I have described the principles of operation of my invention, together with the device which I now consider to 110

represent the best embodiment thereof; but I desire to have it understood that the device shown is only illustrative and that the invention may be carried out by other means and applied to uses other than those above set out.

I claim—

1. A brush comprising a core having brush material secured thereto and bent into a frame-like form with the ends outturned at an angle to the main part of the frame, said core being devoid of bristles for a distance on both sides of said outturned ends, and a cover sleeve enveloping said bared portion of the core and having a hole opening laterally at substantially the lengthwise center thereof through which said bent ends extend, whereby said ends are held against separation and the form of the frame and rigidity thereof is preserved.
2. A brush comprising a core having brush material secured thereto and bent into a frame-like form with the ends outturned at an angle to the main part of the frame, said core being devoid of bristles

for a distance on both sides of said outturned ends, a cover sleeve enveloping said bare portion of the core and having a hole opening laterally at substantially the lengthwise center thereof through which said bent ends extend thereby preserving the rigidity of said frame, and a handle having a hole in its end within which said bent ends are secured.

3. A brush comprising a core having brush material secured thereto and bent into a frame-like form with the ends outturned at an angle to the main part of the frame, said core being devoid of bristles for a distance on both sides of said outturned ends, a cover sleeve enveloping said bare portion of the core and having a hole opening laterally at substantially the lengthwise center thereof through which said bent ends extend thereby preserving the rigidity of said frame, and a handle having a hole in its end within which said bent ends are secured, said handle also having a crosswise groove within which said sleeve is seated.

HENRY CAVE.
